UNITED STATES PATENT OFFICE.

LEON P. LOWE, OF SAN FRANCISCO, CALIFORNIA.

GAS-PURIFIER.

No. 817,650.

Specification of Letters Patent.

Patented April 10, 1906.

Application filed December 13, 1905. Serial No. 291,641.

To all whom it may concern:

Be it known that I, LEON P. LOWE, a citizen of the United States, residing at San Francisco, in the county of San Francisco and State of California, have invented certain new and useful Improvements in Gas-Purifiers, of which the following is a specification.

The object of this invention is to provide a gas-purifier of cheap and simple construction which will be more effective in its use than those heretofore employed.

In the accompanying drawings, Figure 1 is a vertical section of the purifier. Fig. 2 is an enlarged broken perspective view of one of the parts thereof.

Referring to the drawings, 1 represents the casing of the purifier, provided at the top with a removable lid 2. The gas to be purified enters by the inlet 3 at the bottom and escapes by the outlet 4 at the top. In so doing it passes through masses 5 of oxid of iron, which effect the purification of the gas in the manner well known in the art. The present invention resides in the provision which is made for supporting the masses of oxid of iron. The principal objection to purifiers of this class at present in use is that the oxid of iron, which when first used is in a very loose and porous form, after a certain amount of use becomes bound closely together, which tends to interfere with the free flow of the gas. By my improved apparatus I take advantage of the contraction and expansion of the oxid of iron due to changes in temperature in the following manner: I provide one or more trays or boxes 6, there being here shown four such trays superposed upon each other and the lowermost tray resting upon a suitable support 7. In the bottom of the tray is formed a grating 8 of bars sufficiently close together to prevent the oxid of iron falling through. Above said bars are two rows of bars 9, extending parallel with the bars 8 of the grating, but farther apart from each other. Each tray or box is supplied with a sufficient quantity of oxid of iron.

Owing to repeated changes of temperature, due to the intermittent passage of the heated gas and the chemical changes which take place, the oxid of iron is in continual motion, extending when hot and again contracting

when cooling. The masses of oxid of iron are thus forced through the interstices between the upper bars 9, which bars by contact with the masses of oxid of iron so moving retard the surfaces in actual contact with them, while the material out of contact can move more freely. This expansion and contraction therefore tend to continually break up these masses and prevent them assuming a compact permanent form. The motion of the oxid of iron itself, due to changes of temperature, is thus utilized to counteract any tendency of the oxid of iron to form impervious masses, and thus the material is used effectively for the purification of gas without the usual labor incident to changing purifiers, as at present.

While not absolutely necessary, it is preferable to provide a plurality of trays or boxes to contain the oxid of iron, since these trays can with greater ease be removed separately for the purpose of changing the material or for other purposes.

I claim—

1. A gas-purifier having an inlet and an outlet for the gas to be purified and provided with a series of trays or boxes between said inlet and outlet, each box being provided with means for supporting the purifying material while allowing the gas to escape therethrough; and being also provided with stationary bars extending into the purifying material to disintegrate the same by the motion due to changes of temperature, substantially as described.

2. A gas-purifier having an inlet and an outlet for the gas to be purified and provided with a series of trays or boxes between said inlet and outlet, each box being provided with means for supporting the purifying material while allowing the gas to escape therethrough; and being also provided with a plurality of rows of stationary bars extending into the purifying material to disintegrate the same by the motion due to changes of temperature, substantially as described.

In witness whereof I have hereunto set my hand in the presence of two subscribing witnesses.

L. P. LOWE.
